UNITED STATES PATENT OFFICE.

CLYDE S. WRIGHT, OF TOLEDO, OHIO, ASSIGNOR TO THE NATIONAL SUPPLY COMPANY,
OF TOLEDO, OHIO, A CORPORATION OF OHIO.

UNDERREAMER.

1,350,765.

Specification of Letters Patent. Patented Aug. 24, 1920.

Application filed April 5, 1920. Serial No. 371,320.

To all whom it may concern:

Be it known that I CLYDE S. WRIGHT, a citizen of the United States, residing at Toledo, in the county of Lucas and State 5 of Ohio, have invented new and useful Improvements in Underreamers, of which the following is a specification.

My invention relates to underreamers for reaming the sides of wells below their casings.

The object of the present invention is to provide an underreamer simple in construction and containing but few parts. Another object is to reduce the cost of manufacture 15 of underreamers by making the bore of the body circular so that very simple machining operations are required. The cutters have surfaces curved on the arcs of circles wherever possible for the same reason. Another object is to design the parts so that the 20 bits or cutters may be readily inserted into and removed from the body and readily collapsed for insertion of the underreamer into the top of the well casing and for pulling it into the lower end of the casing when 25 it is desired to remove the tool from a well. Other minor objects appear hereinafter.

Referring to the accompanying drawings, Figure 1 is a central longitudinal section of my improved underreamer with the cutters expanded just below the casing, ready to begin a reaming operation or to be withdrawn from the well, parts of the view being in side elevation; Fig. 2, a view similar to 35 Fig. 1, but with the cutters just ready to be collapsed during the operation of pulling the underreamer into the casing; Fig. 3, a view similar to Fig. 2, but with the cutters fully collapsed and the underreamer withdrawn into the casing; Fig. 4, a sectional view of a part of the body of the tool, the view illustrating the method of assembling the underreamer; Fig. 5, a longitudinal section of a part of the body and a 40 side elevation of the cutters and parts co-operating therewith, the view showing the method of collapsing the cutters preparatory to inserting the underreamer into the top of a well casing; and Fig. 6, a cross-section on the line VI—VI of Fig. 2. Fig. 7 is a bottom plan view of the underreamer as shown in Fig. 1.

On the drawings, 1 designates the underreamer body and 2 the sub attachable there- 55 to by the usual tapered pin and box con-

nection 3. The body is hollow or centrally bored from end to end, the hollow having the several sections 4, 5, 6, 7, and 8 of different diameters and shapes, all symmetrically disposed around the longitudinal axis of the 60 body which is in general cylindrical.

The section 4 is at the lower end of the body and is frusto-conical in shape tapering upwardly to the annular shoulder 9. The section 5 is an opening preferably cylindrical, communicating with the section 4 and having its diameter somewhat shorter than that of the upper end of the section 4. The section 6 is a cylindrical opening having a larger diameter than the section 5. The section 8 is a cylindrical bore at the upper end of the body, and is connected to the section 6 by the smaller cylindrical section 7.

Within the sections 4, 5, and 6 are the tangs of the two cutters or bits 10 and 11. 75 The tangs have horizontally curved and upwardly tapering portions 12 fitting the curve and taper of the section 4, and having the shoulders 13 seated against the shoulder 9 when the cutters are in working positions, 80 as shown on Fig. 1. The cutters 10 and 11 have respectively the inner or opposing lugs or shoulders 14 and 15 having the faces 17 and 18 preferably parallel with the body 1, these faces registering or engaging each 85 other when the cutters are in said working position to hold the cutters expanded. The lug 14 has the inclined face or shoulder 19 extending downwardly and outwardly from the lower end of the face 17, and the cutter 90 11 has the correspondingly inclined face or shoulder 20 extending upwardly and outwardly from the upper end of the face 18, so that, when the cutter 11 is moved downwardly with the inclined faces in the same 95 plane, the cutters may move one toward the other during any further downward movement of the cutter 11 until the cutters are fully collapsed, as in Fig. 3, and the inclined faces 19 and 20 lie squarely on each 100 other.

The opposing faces of the portions 12 of the cutter-tangs have recesses, the recess 31 in the cutter 11 being but slightly, if at all, longer than the length of the nut 32 having 105 one side seated therein, while the recess 33 in the cutter 10 extends from the lug 14 up to the level of the top of the recess 31 when the cutters are in working positions. The recess 33 is a seat and slideway for the ad- 110

adjacent side of the nut 32. The recesses 31 and 33 have their inner parts angular to receive the angular sides of the nut to prevent the latter from rotation. See Fig. 6.

5 A helical spring 34 has its lower end resting on the bottom of the section 8 and its upper end supporting the head 35 on the upper end of the rod 36 which extends downwardly through the spring and the section 7, 10 whence it extends down between the tangs of the cutters, its lower end being threaded and screwed into the nut 32. The head 35 has the flat upper extension 37 lying between the two cross pins 38 extending 15 through the walls at the upper end of the body and preventing the rod from turning. Before the pins are inserted the flat extension may have a wrench fitted thereon for turning the rod 36 to screw it into the nut 20 32. The spring 34 causes the nut 32 to hold the cutters with their shoulders 13 against the shoulders 9.

Above the tapered portions 12 of the cutters 10 and 11, the tangs have their respective necks 21 and 22 in the section 5. The cutter 10 has the head 23 at the upper end of its tang, this head being in the section 6 and having its semi-annular lower end seated on the shoulder 24 at the bottom of the 30 section 6, so that the neck 21 of the cutter 10 is about as long as the section 5, this cutter therefore having substantially no longitudinal travel from the position shown on Figs. 1 and 2. Preferably the head 23 extends 35 close to the top of the section 6, the upper end of the head being tapered upwardly so that the cutter 10 may be swung inwardly without lessening the space between this head and the head 25 on the top 40 of the other cutter 11. The head 25 is considerably shorter than the length of the section 6 and stands opposite the tapered section of the head 23 when the cutters are both in working positions. The cutter 11, therefore, has its neck 22 extended considerably 45 up beyond the shoulder 13 and into the section 6, so that the cutter 11 may be drawn downwardly. The opposing portions of the tangs in the section 6 are inclined upwardly 50 and outwardly at 26 to provide clearance for the insertion and removal of the cutter 11. The lower ends of the cutters have the usual cutting edges 27. The cutter 10 has the external shoulder 28 seated on the lower 55 end of the body 1 and is flush therewith when the cutter is in operating position. The cutter 11 has the external shoulder 29 seated on the lower end of the body 1 when the cutter is in working position. The 60 shoulder 29 extends out laterally slightly beyond the outer surface of the body 1 as shown on Fig. 1, the outer part of the shoulder being somewhat rounded or inclined downwardly and outwardly. When the underreamer body is drawn upwardly in the

operation of taking it out of the well, the shoulder 29 will engage the beveled lower end of the well casing 30 and restrain the cutter 11 from traveling upwardly with the body 1 and the cutter 10 until the incline 19 reaches the plane of the incline 20. As the body and the cutter 10 travel farther upwardly the cutter 11 swings toward the cutter 10, the face 19 riding up on the face 20 as the shoulder 29 forces the cutter 11 inwardly and the nut 32 rides down the recess 33. As the tool is drawn up farther into the casing the downwardly flaring faces of the cutters riding into the casing forces the cutters inwardly and the cutter 11 downwardly 75 relatively to the cutter 10 until the cutters are entirely within the casing. The cutter 10 has the external shoulder 28' located somewhat lower than the shoulder 28, so that the described function of the shoulder 29 will not be interfered with. This shoulder 28' assists in the collapsing of the cutters.

The method of assembling the underreamer is partially illustrated in Fig. 4. The cutter 10 is first seated in its normal 90 position with respect to the body 1 by simply inserting its tang therein with the head 23 in the section 6 and the part 12 in the section 4, as shown on Fig. 4. The nut 32 is next inserted into the recess 33, and the cutter 11 is then inserted through the section 4 until the recess 31 comes opposite the nut, whereupon the cutter 11 can be swung toward the cutter 10, the recess 31 covering the adjacent side of the nut. The cutter 11 can then be shoved up to its normal position in the body 1. The rod 36 is then inserted through the spring 34 and between the cutter-tangs and screwed into the nut. The pins 38 are next put in place and the sub 2 screwed on the body 1.

In order to collapse the cutters before introducing the underreamer into the well, a clevis 39 is attached to the cutter 11 by means of the clevis bolt 40 which is passed 110 through the hole 41 in the lug 15. A lever 42 is placed through the clevis with the edge 27 of the cutter 10 as a fulcrum. The lever is then operated in an obvious manner to cause the cutter 11 to be drawn downwardly 115 against the tension of the spring 34 exerted through the rod 36 and the nut 32, the nut 32 riding down the recess 33. When the inclined surfaces on the cutters are opposite, the cutters are moved toward each other until these surfaces interengage. Then the open ring 43 is placed around the cutters to prevent their expanding. The lever and the clevis with its bolt 40 are removed and the cutter end of the underreamer is let down 120 into the casing. The ring 43 is stopped by the end of the casing and the underreamer passes down the casing, the cutters sliding on the inner wall of the casing. When the flat 44 for applying a wrench comes oppo- 130

site the ring 43 the latter may be removed, the gap in the ring being as long as the flat is thick. When the underreamer passes below the casing shoe 30' on the lower end of the casing, the spring 34 acting through the rod 36 and the nut 32 causes the nut by its engagement with the top of the recess 31 to draw the cutter 11 up to its normal working position, which is shown on Fig. 1.

10 It will be noted that, when the cutters are expanded as shown in Fig. 1, the lugs 14 and 15 and the remaining parts of the cutters about the lower end of the body 1 entirely close the bottom of the body, thereby 15 keeping drillings out of the interior of the body. If the drillings have access to the interior of the body, they might become packed in the space between the cutters and beneath the head 25 and prevent the collapsing 20 of the cutters and, consequently, the withdrawal of the underreamer from the well. The lugs 14 and 15 extend entirely across the space between the downward extensions 45 of the sides of the body 1, the 25 inner faces of the extensions being flat and fitting the correspondingly flat faces of the cutters and their lugs 14 and 15.

I do not limit myself to the elements and combinations thereof shown and described, 30 as many changes may be made therein without departing from the spirit of my invention.

I claim:

1. In an underreamer, a pair of opposed 35 expanding cutters having tangs, a body with a bottom recess for the said tangs, means preventing the longitudinal movement of one cutter, a spring controlled rod longitudinally movable in the body, and a head 40 on the rod and in recesses in opposing faces of the tangs, the head being seated against the inner ends of the recesses when the cutters are expanded, the recess in the fixed cutter permitting the said head to travel as 45 the other cutter is moved longitudinally out of the body.

2. In an underreamer, a body having at 50 one end a socket widening toward that end, a pair of expanding cutters having tangs 55 insertible into the socket, means preventing the longitudinal travel of one cutter, and headed means between the cutters yieldingly 60 restraining the longitudinal travel of the

other cutter, the said widening socket providing sufficient room for the second cutter 55 laterally beyond the headed means when it has been longitudinally moved outward a predetermined distance whereby the second cutter may be removed from the socket 60 past the headed means.

3. In an underreamer, a body having at one end a socket widening toward that end, a pair of expanding cutters having tangs insertible into the socket, an inwardly projecting shoulder in the socket, a shoulder on 65 the tang of one cutter coöperating with the first shoulder to prevent the longitudinal travel of that cutter, and means yieldingly restraining the longitudinal travel of the other cutter. 70

4. In an underreamer, a pair of opposed expanding cutters having tangs, a body with a bottom recess for the said tangs, an inwardly projecting shoulder in the socket, a shoulder on the tang of one cutter coöperating with the first shoulder to prevent the longitudinal travel of that cutter, and spring controlled means yieldingly restraining longitudinal movement of the other cutter, whereby the latter cutter may upon 80 such movement be removed from the body. 85

5. In an underreamer, a body having an end socket, cutters having tangs in the socket, means preventing longitudinal travel of one cutter, the other cutter having longitudinal travel, means yieldingly restraining the travel of the second cutter, abutting faces on the cutters to hold them expanded when the second cutter is in its working position, and a head and shoulder connection between the second cutter and the socket to limit the outward longitudinal movement of the second cutter when the cutters are collapsed, shoulders retreating below the said face on the first cutter and 90 above the said face on the second cutter and permitting the collapse of the cutters upon a relative longitudinal travel of the second cutter and the remainder of the underreamer in a direction to remove the tang of 95 the second cutter partially from the said socket. 100

Signed at Toledo, Ohio, this 30th day of March, 1920.

CLYDE S. WRIGHT.
